BINDING MACHINE

Adrien L. Jalbert, Lewiston, Maine, assignor of
fifty per cent to Emile R. Jalbert, Lewiston,
Maine

Application June 19, 1950, Serial No. 168,869

10 Claims. (Cl. 12—17)

1

This invention relates to new and useful improvements in binding and/or covering machines, and the primary object of the present invention is to provide a machine for binding the edges of a shoe platform and which is also adapted for applying binding tape to the edges of any suitable article, such as book coverings, or the like.

Another very important object of the present invention is to provide a binding machine involving a pair of reciprocating hammers and a spool located behind the hammers and coacting with the hammers to fold a binding tape into a channel as the binding tape is forced between the hammers and against the spool by an article that is to be bound.

Yet another object of the present invention is to provide a binding or covering machine of the aforementioned character involving a novel and improved mechanism for tensioning the binding tape when the tape is forced between the hammers and against the spool.

Another object of the present invention is to provide a binding machine wherein the binding-tape tensioning means involves a sliding wedge which is manually actuated to activate the tensioning means.

A further object of the present invention is to provide a binding machine including a pair of vertically swingable, spring connected hammers and a rotary cam for simultaneously riding against the hammers to spread and then release the hammers, whereupon the hammers will be urged toward each other to tamp or clamp a binding tape against both faces of an article being bound.

A still further aim of the present invention is to provide a binding machine that is simple and practical in construction, strong and reliable in use, small and compact in structure, efficient and durable in operation, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view of the present invention and showing a shoe platform and binding tape in dotted lines on the machine;

Figure 2 is a top plan view of Figure 1 and showing the binding tape in full lines;

Figure 3 is a vertical sectional view taken sub-

2

stantially on the plane of section line 3—3 of Figure 1;

Figure 4 is a view similar to Figure 1 but showing the tape gauge and the tape guide removed, and with parts broken away for the convenience of explanation;

Figure 5 is an end view of Figure 1;

Figure 6 is an enlarged vertical sectional view taken substantially on the plane of section line 6—6 of Figure 1;

Figure 7 is a detail vertical sectional view showing the tensioning means actuator mechanism; and

Figure 8 is an enlarged vertical sectional view taken substantially on the plane of section line 8—8 of Figure 3.

Referring now to the drawings in detail, wherein, for the purpose of illustration, there is disclosed a preferred embodiment of the present invention, the numeral 10 represents a frame having a pair of vertically swingable, upper and lower hammers 12 and 14 on one of its end walls. The upper hammer 12 includes a supporting arm 16 that is secured to the frame through the medium of a horizontal pivot 18 and the lower hammer 14 also includes a supporting arm 20 that is pivoted to the frame by a horizontal pivot 22.

The arms 16 and 20 support laterally projecting pins 24 and 26 that engage the ends of a coil spring 28. The spring 28 yieldingly urges the arms 16, 20 and hence the hammers 12, 14 toward each other as shown best in Figure 5. A vertical guide strap 30 is secured intermediate its ends to the frame 10 and the arms 16 and 20 are positioned between the strap 30 and the end wall of the frame supporting the strap 30.

A longitudinally extending shaft 32 is carried by the frame 10 and supports at one of its ends a cam 34 having diametrically opposed lobes for riding against the lower edge of the arm 16 and the upper edge of the arm 20 to urge the arms apart, whereupon the spring 28 will return the hammers 12, 14 to a position for tamping binding tape against an article.

The arm 16 is integrally formed with a sleeve 36 that slidably receives the hammer 12 and which supports a set screw 38 that is manually adjustable to retain the hammer 12 vertically adjusted in the sleeve 36.

The end of the shaft 32 remote from the cam 34 supports a pulley 40 that is connected by a pulley belt 42 to a suitable source of power such as a motor (not shown) which is located

close to the frame 10. The shaft 32 is received in bushings 44 at the ends of the frame.

A holding arm 46 is detachably secured to and held stationary on the frame 10 and underlies the arm 20. The arm 46 is provided with a forward offset portion 48 that supports a plurality of guide posts 50 whose upper hollow and conical ends 52 receive balls 54 that are supported on lugs 56 within the ends 52.

A pair of horizontal ears 58 project forwardly from the frame 10 adjacent the hammers and supports a vertical spool 60 that parallels the hammers 12, 14 and which is located behind the hammers. The area of the roller or spool between its upper and lower flanges registers with the space between the hammers for a purpose later to be more fully described.

The forward flat face of the frame 10 supports a bracket 62 having an upper horizontal flange 64 that rotatably supports a vertical adjusting screw 66. A traveling member or nut 68 is threaded on the screw 66 and is rigidly secured to the inner leg portion 70 of a guide channel 72. The guide channel extends longitudinally of the frame and includes an exit end 74 that is spaced from the spool 60. The nut 68 is fixed to a guide plate 76 whose vertical side edges are slidable in keyways 78 in the sides of the bracket 62.

The forward face of the frame 10 supports a shelf or plate 80 on which there is mounted a horizontally swingable member or arm 82 that is secured to the shelf 80 by a horizontal pivot 84. One end of the member 82 is provided with an upstanding post 86 that supports a vertical pressure roller 88. A horizontal screw 90 is threaded in a horizontal aperture in the arm 82 and supports at its inner end a disk 92 that enters a horizontal recess 94 in the frame 10. A spring 96 seated within the recess 94 bears against the disk 92 and yieldingly urges the roller 88 through a slot S in the outer flange of channel 72 and against the vertical face of the inner flange of the guide channel at the exit end of the guide channel.

A guide sleeve 98 is secured to the plate 80 on the frame remote from the hammers and slidably receives a vertical wedge 100 to which there is threaded a screw 102. The screw 102 is attached to a vertically swingable foot lever or pedal 104 by a connecting member 106. The sleeve 98 is provided with a horizontal slot 108 that slidably receives one end of the member 82, as shown best in Figure 7. A spring 110 is mounted in the lower end of the sleeve 98 and urges the wedge 100 to its raised position and against the member 82.

As the pedal 104 is pressed downwardly, the wedge 100 releases the member 82 and the spring 96 urges the member 82 to a position whereby the roller 88 is forced toward the frame.

The leg portion 70 of the channel 72 is provided with an end extension 112 that enters a vertical slot 114 in a gauge member 116. A set screw 118 is carried by the member 116 and is threaded in the upper edge of the extension 112 to adjust the member 116 vertically of the guide channel and so that the lower flat and horizontal face 120 of the member 116 may bear against the upper edge of a binding tape T.

A vertical turn roller 122 is mounted on the guide channel or the member 112 and is positioned relatively close to the spool 60, as shown in Figures 1 and 2, to curve or turn the tape.

In practical use of the present invention, the binding tape T is extended through the guide

channel 72, behind the roller 88 and in front of the hammers 12 and 14. Next, the article A to be bound, such as a shoe platform, is forced between the hammers and toward the spool 60 so that the tape T will be folded into a channel. The tape will be forced against the spool 60 and between the upper and lower flanges of the spool, by the article A, as shown in Figure 6.

Then, the pedal 104 is depressed to cause the wedge 100 to release the member 82, whereupon the spring 96 urges the roller 88 against the binding tape T and the binding tape against the flat vertical face of the frame to retain the tape taut and tensioned.

As the pedal 104 is released, the shaft 32 rotates and the cam 34 reciprocates the hammers to tamp the binding tape against both faces of the article A. The tape T is preferably coated with adhesive or the article A is coated with adhesive to retain the tape on the article and the article is rollingly supported upon the rollers or balls 54 as it is fed between the hammers and toward the spool.

After the tape has been attached to the article, as the article is swung counter-clockwise, the tape will be pulled through the guide channel and the tape is tensioned at will by a depression of the pedal 104.

Having described the invention, what is claimed as new is:

1. A binding machine comprising upper and lower vertically swingable hammers, a vertical spool paralleling said hammers and located behind said hammers, said spool having upper and lower flanges adapted to receive therebetween an article to be bound, said hammers adapted to tamp a binding tape on an article received between the hammers and the upper and lower flanges, guide means mounted on the machine and leading to said spool, means operatively connected to said hammers for selectively swinging the hammers toward and away from each other, and additional means on the machine for tensioning binding tape as an article is forced toward the spool to urge a binding tape between the upper and lower flanges of the spool.

2. A binding machine comprising upper and lower vertically swingable hammers, a vertical spool paralleling said hammers and located behind said hammers, said spool having upper and lower flanges adapted to receive therebetween an article to be bound, said hammers adapted to tamp a binding tape on an article received between the hammers and the upper and lower flanges, a horizontally disposed vertically slideable guide on the machine, means connected to said guide for vertically adjusting the guide, a binding-tape gauge on the machine at one end of the guide, means operatively connected to said hammers for selectively swinging the hammers toward and away from each other, and additional means on the machine for tensioning binding tape that is forced against the spool by an article received between the hammers.

3. A binding machine comprising upper and lower vertically swingable hammers, a vertical spool paralleling said hammers and located behind said hammers, said spool having upper and lower flanges adapted to receive therebetween an article to be bound, said hammers adapted to tamp a binding tape on an article received between the hammers and the upper and lower flanges, guide means mounted on the machine and leading to said spool, means operatively connected to said hammers for selectively swinging the hammers toward and away from each other,

and additional means on the machine for tensioning binding tape as an article is forced toward the spool to urge a binding tape between the upper and lower flanges of the spool, said hammers including supporting arms pivoted to the machine, and said means operatively connected to said hammers including a coil spring terminally attached to said arms, and a rotary cam positioned between and adapted to ride against both of said arms to spread the arms against action of said coil spring.

4. The combination of claim 1 wherein said additional means includes a horizontally swinging member, a vertical roller at one end of said member, spring means acting on said member and urging the roller to a position for bearing against a binding tape, a sliding wedge urging the member in a direction to tension the spring means, and further means for releasing said wedge.

5. The combination of claim 1 wherein said additional means includes a horizontally swinging member, a vertical roller at one end of said member, spring means acting on said member and urging the roller to a position for bearing against a binding tape, a sliding wedge urging the member in a direction to tension the spring means, and a foot pedal connected to said wedge and being manually depressed to release the wedge from engagement with said member.

6. A binding machine comprising a frame, upper and lower vertically swingable hammers mounted on said frame for receiving an article to be bound therebetween, a vertical spool on said frame paralleling said hammers and having upper and lower flanges to receive an article to be bound therebetween, a guide channel mounted on the frame for receiving and guiding binding tape, said guide channel including an exit end located relatively close to said spool, said guide channel including inner and outer vertical flanges, said outer vertical flange having a slot at the exit end of said guide channel, means carried by the frame and disposed at the exit end of said channel and movable through the slot for urging a binding tape against said inner flange and thereby tension a binding tape, and means also mounted on the frame and operatively connected to the hammers for selectively urging said hammers toward and away from each other.

7. A binding machine comprising a frame, upper and lower vertically swingable hammers mounted on said frame for receiving an article to be bound therebetween, a vertical spool on said frame paralleling said hammers and having upper and lower flanges to receive an article to be bound therebetween, a guide channel mounted on the frame for receiving and guiding binding tape, and including inner and outer vertical flanges, said guide channel including an exit end located relatively close to said spool and having a slot in its outer flange, a horizontally swingable arm

on said frame, an upstanding pressure roller at one end of said arm located at the exit end of said guide channel, a spring means acting on said arm and urging said roller through said slot and toward said inner vertical flange to force a binding tape leaving the exit end of said channel against said inner flange, and manually actuated means forcing the roller away from said flat portion.

10 8. A binding machine comprising a frame, upper and lower vertically swingable hammers mounted on said frame for receiving an article to be bound therebetween, a vertical spool on said frame paralleling said hammers and having upper and lower flanges to receive an article to be bound therebetween, a guide channel mounted on the frame for receiving and guiding binding tape, said guide channel including an exit end located relatively close to said spool, said guide channel including flat vertical inner and outer flanges, said outer flange having a slot located at the exit end of said guide channel, means carried by the frame and positioned at the exit end of said channel and movable through said slot for urging a binding tape against said inner flange and thereby tension a binding tape, means also mounted on the frame and operatively connected to the hammers for selectively urging said hammers toward and away from each other, said last-named means including a coil spring terminally attached to said hammers and yieldingly urging said hammers toward each other, and a rotary cam positioned between said hammers and having diametrically opposed cam lobes for riding against said hammers to spread the hammers.

20 9. The combination of claim 6 and a vertically adjustable gauge member mounted on said frame adjacent said spool for engaging the upper edge of a binding tape leaving the channel.

40 10. A binding machine comprising upper and lower vertically swingable hammers, a vertical spool paralleling said hammers and located behind said hammers, said spool having upper and lower flanges adapted to receive therebetween an article to be bound, said hammers adapted to tamp a binding tape on an article received between the hammers and the upper and lower flanges, guide means mounted on the machine and leading to said spool, and means operatively connected to said hammers for selectively swinging said hammers toward and away from each other.
